UNITED STATES PATENT OFFICE.

JULES DUHON, OF GOSS, LOUISIANA, ASSIGNOR OF ONE-HALF TO E. H. WHITE, OF DE SOTO PARISH, LOUISIANA.

DEEP-WELL PUMP.

1,377,763.

Specification of Letters Patent. Patented May 10, 1921.

Original application filed July 28, 1920, Serial No. 399,488. Divided and this application filed March 14, 1921. Serial No. 451,941.

To all whom it may concern:

Be it known that I, JULES DUHON, a citizen of the United States, residing at Goss, in the parish of De Soto and State of Louisiana, have invented certain new and useful Improvements in Deep-Well Pumps, of which the following is a specification, reference being had to the accompanying drawings.

10 This invention relates to certain improvements in deep well pumps, and it is an object of the invention to provide a novel and improved structure of this general character embodying means whereby the traveling 15 valve may be conveniently withdrawn from its working position without the necessity of pulling out the working barrel.

15 The invention consists in the details of construction and in the combination and arrangement of the several parts of my improved deep well pump whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is an enlarged fragmentary view partly in elevation and partly in longitudinal section illustrating a barrel structure constructed in accordance with an embodiment of my invention;

Fig. 2 is a sectional view taken substantially on the line 2--2 of Fig. 1; and

Fig. 3 is a sectional view taken substantially on the line 3--3 of Fig. 1.

As disclosed in the accompanying drawings, B denotes a working barrel preferably of the type disclosed in my prior application, Serial No. 399,488, filed July 28, 1920, and of which the present application is a division, said barrel embodying the standing valve 42. Working within the barrel B is the traveling valve V.

50 The traveling valve V is of a conventional type and includes the leather cups or gaskets 45. In threaded engagement with the upper end portion of the traveling valve V in a well known manner is the lower end portion

of the valve stem 46. The lower portion 46^a of the stem 46 is angular in cross section while the upper portion 46^b is circular. The stem 46 works through a lift cage 47 operatively engaged with the upper end portion of the working barrel B preferably through the instrumentality of left hand threads.

The lower portion of the bore 48 of the cage 47 is angular in cross section to snugly receive the angular lower portion 46^a of the stem 46 while the upper portion of said bore 48 of the cage is cylindrical and through which the cylindrical portion 46^b of the stem 46 is snugly disposed.

The upper end portion of the stem 46 is adapted to be coupled as at 47^a, in a conventional manner with the lower end portion of a pump rod 50.

Under normal conditions, the strokes of the rod 50 permit the valve V to have its requisite reciprocation within the barrel B but when it is desired to withdraw the valve V to renew the leather cups or gaskets 45 or to otherwise repair the valve V, the rod 50 is pulled upwardly until the angular portion 46^a of the stem 46 engages within the angular portion of the bore 48 of the cage 47 and upon requisite rotation being given to the rod 50, the cage 47 will be disengaged from the barrel B, whereupon the valve V can be easily removed and without the necessity of withdrawing the barrel B and the remaining structural elements of the mechanism positioned within the tubing T and the parts carried thereby. With the valve V removed, the working barrel and the parts carried thereby can be readily removed by engaging within the upper or open end of the barrel B a suitable fishing tool.

From the foregoing description it is thought to be obvious that a deep well pump constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A deep well pump comprising, in combination, a tubing, a working barrel positioned within the tubing and provided with a stand valve, a traveling valve working within the barrel, a cage carried by the upper end portion of the barrel, and a stem carried by the traveling valve and disposed through the cage, a portion of the bore of the cage being angular in cross section and the lower portion of the stem of the traveling valve being of a cross section similar to the angular cross sectional portion of the bore of the cage.
- 15 2. A deep well pump comprising, in combination, a tubing, a working barrel positioned within the tubing and provided with a stand valve, a traveling valve working within the barrel, a cage carried by the upper end portion of the barrel, and a stem carried by the traveling valve and disposed through the cage, a portion of the bore of the cage being angular in cross section and the lower portion of the stem of the traveling valve being of a cross section similar to the angular cross sectional portion of the bore of the cage.
- 20
- 25

of the cage, said cage being in threaded engagement with the barrel.

3. In combination with the working barrel for a deep well pump, a traveling valve 30 working therein, the bore of the barrel at the upper part thereof being angular in cross section, and a stem carried by the traveling valve and disposed through the angular portion of the bore of the barrel, the lower 35 portion of the stem being of a cross section similar to the angular cross sectional portion of the bore of the barrel.

4. In combination with the working barrel for a deep well pump, a traveling valve 40 working within the barrel, a cage carried by the upper portion of the barrel, and a stem carried by the traveling valve and disposed through the cage, a portion of the bore of the cage being angular in cross section and the lower portion of the stem of the traveling valve being of a cross section similar to the angular cross sectional portion of the bore of the cage.

In testimony whereof I hereunto affix my 50 signature.

JULES DUHON.
